(57) **CLAIM**

The ornamental design for a container cover, as shown and described.

DESCRIPTION

FIG. 1 is a top and side perspective view of my container cover according to a first embodiment of my new design; FIG. 2 is a bottom and side perspective view thereof; FIG. 3 is a front elevation view thereof; FIG. 4 is a rear elevation view thereof; FIG. 5 is a left side elevation view thereof; FIG. 6 is a right side elevation view thereof; FIG. 7 is a top plan view thereof; FIG. 8 is a bottom plan view thereof; FIG. 9 is a side elevation view thereof showing the container cover attached to an exemplary container bottom; FIG. 10 is a top and side perspective view of my container cover according to a second embodiment of my new design; FIG. 11 is a bottom and side perspective view thereof; FIG. 12 is a front elevation view thereof; FIG. 13 is a rear elevation view thereof; FIG. 14 is a left side elevation view thereof; FIG. 15 is a right side elevation view thereof; FIG. 16 is a top plan view thereof; FIG. 17 is a bottom plan view thereof; and, FIG. 18 is a side elevation view thereof showing the container cover attached to an exemplary container bottom. The broken lines illustrate exemplary environment and form no part of the claimed design.
